UNITED STATES PATENT OFFICE.

FREDERICK GEORGE SEIFARTH, OF CHICAGO, ILLINOIS, ASSIGNOR TO FRANK A. SMITH, OF CHICAGO, ILLINOIS.

KNITTING APPLIANCE.

1,318,465.

Specification of Letters Patent. Patented Oct. 14, 1919.

Application filed January 4, 1918. Serial No. 210,242.

To all whom it may concern:

Be it known that I, FREDERICK GEORGE SEIFARTH, a citizen of the United States of America, and a resident of Chicago, county 5 of Cook, and State of Illinois, have invented certain new and useful Improvements in Knitting Appliances, of which the following is a specification.

This invention relates to knitting appliances adapted particularly for manual use, and the main objects of the invention are to provide means of improved form adapted to facilitate greater speed and convenience in doing the kind of knitting work hereinafter 10 described.

The main objects of this invention are to provide knitting means of improved form adapted to facilitate greater speed and accuracy; to provide a knitting device or 15 holder adapted for use with a single needle to produce either flat or cylindrical fabrics, such as socks, sweaters, or the like; to provide a unitary knitting holder comprising a body plate of suitable form and provided 20 with mesh holding arms adapted for forming or stamping from sheet material; to provide a multiple armed holder formed with mesh supports or stop means at or adjacent to the base of the arms and formed or provided 25 with means adapted to facilitate proper insertion and manipulation of the needle in knitting; and to provide in a knitting device of the character described a plurality of arms mutually related and formed 30 to prevent accidental dropping of meshes or 35 stitches.

Several illustrative embodiments of this invention are shown in the accompanying drawings, in which:

40 Figure 1 is an axial section of a knitting device or holder.

Fig. 2 is a perspective view of the embodiment illustrated by Fig. 1.

45 Fig. 3 is a plan of a disk-shaped or discoidal form of knitting holder.

Fig. 4 is a cross section on the line 4—4 of Fig. 3.

Fig. 5 is a plan of the back side of the embodiment shown in Fig. 3.

50 Fig. 6 is an axial section of a large annular form of holder adapted for use in knitting socks and the like.

Fig. 7 is a perspective view of a rectilinear

form of holder adapted for knitting flat fabrics.

55

Fig. 8 is a perspective view of a needle adapted for use in connection with any of the foregoing embodiments.

Fig. 9 is a cross section showing a modified form adapted for substitution in either 60 of Figs. 6 and 7, the tips of the arms being formed to prevent removal of the work by mere pulling on the yarn or other material.

In the embodiment shown in Fig. 1, the knitting holder 1 comprises a flat centrally 65 apertured disk or annulus 2, preferably made of sheet metal, and a handle 3 to which the annulus is attached, said annulus being provided with upstanding arms or mesh holders 4, and the handle being tubular in 70 shape and disposed coaxially with said annulus. Said parts may be fastened together by any suitable means, preferably in the form of downwardly projecting brads 5 struck out from the sheet material comprised by the annulus, three such brads being 75 well adapted to hold the parts together as shown in Fig. 2.

In order to best facilitate operation of the device, that is to say, in order to give free 80 and ready access for the hook or needle 6, the mesh holding arms 4 are set forward somewhat toward the center, and away from the main body of the annulus, as illustrated in Fig. 2 and as well shown in Fig. 3. The 85 said arms 4 are preferably inclined outwardly and divergently in order that the meshes of the knitting fabric supported on said arms respectively may the more definitely and positively tend to stay in their 90 normal position at the angle formed by said arms 4 with the inwardly projecting part 7 of the annulus proper.

The apertures or indentations 8 in the annulus between said arms are each considerably wider than the working point of the needle to be used, and provide ready access therefor. The upper ends or tips of the arms are turned abruptly outward, as at 9, so as to positively prevent dropping 100 of stitches or accidental removal or escape of the meshes from the holder before the work is finished.

When in use the knitted fabric, such as shown in Fig. 4, hangs in the cylindrical 105 passage or guideway 10, which is made flar-

ing at the upper end, as at 11, so that the upper end face 12 of the handle may register substantially with the main body part of the annulus 2, and so avoid blocking the needle 5 working apertures 8.

Referring to the embodiment shown in Figs. 3 and 4, the holder as a whole is rather flat and discoidal in shape, and in the form shown its general form is double convex. This embodiment comprises a pair of annulus members 13 and 14 disposed side by side, that is to say, one over the other coaxially, and in spaced relation, the outer edge parts being connected rigidly. The 15 front or upper annulus 13 may be made mainly like the corresponding face part 2 of Fig. 1.

The outer edges of the front and back members 13 and 14 are connected by a flaring 20 ring-like strip or band 15, the inner front edge of which is crimped or turned inwardly to overlap the outer edge of the face plate 13, the outer edge being positively interlocked with the back plate 14. The said 25 front plate is held in its spaced relation respecting the back plate by means of the lugs or arms 16, similar to the brads 5 of Fig. 1, serving as braces instead of fasteners. The back plate 14 is overlaid with a sheet 30 of suitable finishing material 17, preferably thin sheet celluloid. The inner edge of the celluloid is crimped over the corresponding edge of the back plate as at 18. The outer edge of the celluloid is turned 35 up over the outer peripheral flange 19 of the back plate and turned in between said flange and the ring 15, thus providing a very neat and workmanlike appearance as well as a strong and durable construction. 40 The face plate 13 is apertured centrally and provided with upstanding arms 20 corresponding in character and purpose with the arms 4 of Fig. 1. Said arms are provided with outwardly turned tips or heads 21, to 45 prevent accidental release of the fabric to be held. Apertures 22 are provided between the arms 20 to give ready access for the needle 6 substantially as in the device of Fig. 2. When in use the meshes 23 are 50 supported on said arms and the main body of the fabric 24 feeds downward through the central aperture as the work progresses. This embodiment is adapted to serve well as an inexpensive advertising novelty.

55 In the device shown in Fig. 6, the invention is embodied in a commercial form of holder suitable for knitting socks and the like. In this instance there is provided a ring-shaped frame or body part 28, which 60 may be made of wood or any other suitable material, and an arm bearing part 29 mounted thereon, the latter part preferably being of the nature of sheet material and being attached to the inner face of the 65 ring 28 and provided with arms 30 extend-

ing upward on one edge. The tips of said arms are suitably formed, as at 31, to prevent accidental removal of the meshes supported by said arms when the device is in use, and for this purpose the said tips are 70 enlarged somewhat and formed concavo-convex with the convex side facing outward. This form of tip is adapted to provide a smooth working face free from sharp edges, such as might injure the meshes. 75

The part 29 is ring-shaped, and is apertured as at the points 32 between the arms 30. The body part or ring 28 is also apertured as at 32' in registry with the inner ring apertures. The upper face of the ring 80 28 between the apertures 32' extends inward to the arms 30 and thereby provides shoulders 28' whereon the corresponding meshes may rest and thereby support the fabric in a manner adapted to facilitate 85 efficient operation of the needle 6 when the device is in use. The said inner ring 29 may be made by cutting up long strips or stock punchings into suitable lengths so that when one of same is bent into cylindrical shape the ends may be brazed together or the abutting ends, as shown at 33, may be secured by means of screws 34, such as are used also for fastening the ring 29 in place within the frame ring 28. 90 95

In order that this form of knitting holder may be conveniently supported, especially when made in the larger sizes, provision is made for attaching legs 35 which may be of suitable length to hold the ring 28 at a 100 convenient height above the table or other support. Said legs may fit interchangeably in sockets 35'.

In the embodiment shown in Fig. 7, the construction is substantially like that shown 105 in Fig. 6, except that the holder instead of being made circular is made straight. In this instance the holder comprises a rod or bar 36 of any desired length corresponding with the width of the fabric to be knitted. 110 On one side of said rod is attached the sheet metal strip or punching 37 formed with upstanding arms 38 having heads 39 corresponding with the similar parts shown on Fig. 6. The rod 36 and plate 37 are so 115 formed as to provide indentations or recesses 40 between the arms 38, in order to facilitate insertion of the needle, the meshes being supported on the shoulders 41 back of the arms 38 and between the recesses 40. 120

The embodiment of Fig. 6 though designed primarily for round or tubular fabrics may of course be used for knitting flat goods by knitting back and forth on the series of arms 30, or such part thereof as 125 may be desired, substantially as on the device of Fig. 7.

The embodiments of Figs. 1 to 5 are adapted mainly for use as educational toys and advertising specialties, but Figs. 6 and 130

7 represent embodiments adapted to supply a present need for improvements in manual means for manufacturing knitted garments suitable for general wear and especially for 5 army use.

Each of the forms shown may be made in a size suitable for use as a toy, and each may carry advertising or educational matter or other legends as may be desired either 10 on the face, back, or sides.

Although several embodiments of this invention are herein shown and described, it will be understood that numerous details of the constructions shown may be altered or 15 omitted without departing from the spirit of this invention as defined by the following claims.

I claim—

1. A knitting device of the character described, comprising a frame or body part 20 having upstanding arms disposed in a series along an edge thereof adapted for supporting the meshes of the fabric knitted, apertures being provided between said arms and 25 back of the points of support adapted to facilitate insertion and due manipulation of a needle.

2. A device of the character described,

comprising a mesh supporting member adapted for formation from sheet material, 30 said member having a series of upstanding arms on one edge, shoulders at or adjacent to the base of said arms whereon the meshes may rest, and apertures between said shoulders adapted to facilitate entry of a needle. 35

3. A device of the character described, comprising a frame provided with a series of arms adapted to hold the several meshes on one edge of the fabric, means for holding the meshes in a definite position with respect to 40 said arms, and a needle adapted for insertion between said arms for forming meshes, apertures being provided between said arms below and back of the mesh holding points for admitting said needle. 45

4. A knitting device of the character described, comprising in combination a supporting base part and a flat sheet metal work-holding part fastened thereon, the latter part having a serrated working edge 50 formed with upwardly turned work-holding points and alternately arranged recesses whereby use of the needle is facilitated.

Signed at Chicago this 29th day of December, 1917.

FREDERICK GEORGE SEIFARTH.
